CLAIM

The ornamental design for a vacuum cleaner, as shown and described.

DESCRIPTION

FIG. 1 is a top, front, right side perspective view of a vacuum cleaner showing our new design;
FIG. 2 is a front elevational view thereof;
FIG. 3 is a right side elevational view thereof;
FIG. 4 is a left side elevational view thereof;
FIG. 5 is a top plan view thereof;
FIG. 6 is a rear elevational view thereof;
FIG. 7 is a top, rear, right side perspective view thereof; and,
FIG. 8 is a top, rear, left side perspective view thereof.
The features shown in broken lines are included for environmental purposes and form no part of the claimed design.
